UNITED STATES PATENT OFFICE.

ELOF BENSON, OF NEWTON HIGHLANDS, AND FRANCIS H. WILLIAMS, OF BOSTON,
MASSACHUSETTS.

PERCEPTION OF RADIANT ENERGY.

Application filed April 13, 1918. Serial No. 228,324.

To all whom it may concern.:

Be it known that we, ELOF BENSON and FRANCIS H. WILLIAMS, citizens of the United States of America, and residents, respectively, of Newton Highlands, in the county of Middlesex, and Boston, in the county of Suffolk, both in the State of Massachusetts, have invented new and useful Improvements in the Perception of Radiant Energy, of which the following is a specification.

This invention relates to detection or perception as for signaling, telephony, telegraphy, phonographic sound recording and reproduction, and other purposes, of radiant or wave-motion energy, including acoustic, radiant electric, magnetic and other waves of wave-lengths not capable of direct sensory perception as light or infra-red heat.

20 The invention utilizes and operates upon principles applying the discovery of certain phenomena indicating the direct conversion into electrical currents, impulses or oscillations in a class of conductors [the electric manifestation in the conductor then being readily perceptible with the aid of known instruments] of such wave-motions or radiations. Radiations or wave-motions of the kind referred to, except electric waves, have 30 not hitherto been observed to have the power to be converted into perceptible electrical currents or impulses, or directly to excite such currents or impulses in a conductor.

Perception of or useful effect from radiations or wave-motions either of ponderable matter or the ether heretofore has been dependent upon receiving apparatus of marked limitations, such as the well-known receiving devices for electric radiations 40 comprising oscillatory resonating circuits, including therein electric wave or oscillation rectifiers, thermo-electric couples, coherers or other detectors operating by changes of ohmic resistance, electrolytic changes, changes of ionic condition of a gaseous or other dielectric, by conversion to heat, by changes of electrostatic capacity, by demagnetization of a magnet, or by polar selectivity to current flow; and all as heretofore known, being sensitive only to electric radiant energy. Or such perception, for sound only, hitherto has been dependent upon hearing, assisted by direct amplification of the sound wave, or the operation of 55 sound transmitters or microphones charac-

terized by movable diaphragms or other parts bodily or dynamically vibrated by an incoming sound-wave desired to be perceived, the last mentioned apparatus for sound perception not being usefully sensitive directly to perceive electric radiations.

60 This invention comprises a new art or method of perceiving, detecting or rendering useful for the purposes indicated and other purposes, wave-energy of the types mentioned, as well as a genus of apparatus for practising the said method.

The new art comprises simultaneous detection of electric radiations or Hertz waves, inductive or radiant magnetic disturbances, 70 and sounds, apparatus employed for the practice of the invention being capable if desired of simultaneously receiving and converting into electric currents, impulses, or oscillations radiant electric energy such as 75 ordinary wireless waves, inductive changes in the field surrounding the detector, and the acoustic vibrations of ponderable matter.

In certain forms of the invention, capacity 80 to perceive an acoustic, magnetic or electric wave, or either, impinging on the apparatus employed is accompanied by capacity to detect or perceive thereby with substantial accuracy the direction of propagation of the sound or electric radiation, and the invention 85 also includes an art of and apparatus for determining the direction of propagation of such waves at the place at which they are perceived or observed.

The apparatus selected to be herein shown 90 and described as instances of one subordinate genus of the broader genus of apparatus adapted to be used in the practice of the art or method forming a part of the invention, is characteristically capable of developing a perceptible electric energy therein in response to exterior excitation by acoustic, radiant magnetic, electric and other radiations independently of the dynamic motion, so far as known, of any of its parts, and independently of any source of energy within the apparatus other than the energy received from such radiation or wave-motion.

Radiations or wave-motions capable of so exciting the illustrative apparatus comprise 105 sound waves in air or denser media, lying within a selective range of pitch or wavelength variable with changes in the apparatus; vibrations of acoustic type inaudible as sound; radiant electric and magnetic waves, 110

and changes in the magnetic or inductive field at the apparatus, and it may well be that apparatus of the genus in question is also capable of excitation by other radiations whether of ponderable matter or etheric, as yet undetermined or not fully understood, and not essential to be understood in order to explain or practically to utilize the principles and modes of operation of the simple apparatus employed to perceive known types of energy received from distant sources and herein described as the best instances of which we are now aware of devices for practicing the method or art.

We are aware of mere uses to which the invention may be applied without substantial change and within the expected skill of artisans almost as numerous as the arts aided by the application of electricity and for that reason we shall undertake to describe in this specification not all but only one specific application to use, with such illustrative instances of the mode of and apparatus for effecting this result as are necessary to understand it. The devices are particularly useful for the selective determination of marine and submarine sounds, of marine and under-water emissions of an inductive or magnetic nature, and of the direction of their propagation, and the specific use elected to be described relates to the distant detection of a submarine or surface vessel by such sounds or other radiations proceeding from the vessel, and the determination of its bearing and motions in respect to the observer.

Figure 31 is a diagram of circuit connections.

During the course of a series of experiments on forms of devices adapted to receive and transmit faint sounds received under water, we were led to conclude that the vigor and nature of extraneous sounds occurring in the neighborhood of an observing vessel or occasioned by the motion through the water of the audition instrument itself, or the necessary result of sounds emitted by traffic on or in the water intended to be observed, were such as to prevent useful observation under the very conditions in which such observation would prove of the most utility; for instance, under conditions in which it is important to detect the approach and movement of an enemy submarine vessel or of an automobile torpedo, or to pick up signals or telephonic signals from another ship or shore station from a vessel under way. The difficulty common to all of the prior art apparatus of which we are aware has been

too great sensitiveness of the detector and transmitter device to all sounds, especially to noises made on the ship carrying the observing instrument or resulting from the progress of the ship or detector through the water.

Not then being able to dispense with some form of vibrated diaphragm, we conceived the useful possibility of rendering much less sensitive than heretofore a transmitter,

such as the commonly employed microphone transmitter, and then observing the indications transmitted by such an instrument with the aid of an amplifying device, either 5 the transmitter or the amplifier being adapted selectively to magnify or amplify the impulses transmitted with respect to the class of sounds sought to be perceived, and to suppress or not so much to magnify the 10 indications of extraneous noises acting to disturb the observation.

For this purpose we conceived using together a sensitive oscillation amplifier of any well-known type, and a circuit containing 15 a source of energy, the amplifier, and a detector of selective and little sensitiveness. These experiments led to the discovery of a class of phenomena which we are at present able to assign to no wholly satisfactory 20 theory, although by hypothesis presently to be referred to we have been able to design instruments for predicted results and to obtain complete and satisfactory confirmation in operation of the predicted behavior 25 of the instruments. We will therefore explain the phenomena in question by reference to experimental reactions of apparatus in order to enable the operation of the devices and practice of the art involved to be 30 clearly understood, whatever the underlying physical explanation may be.

The apparatus comprises two parts, a sensitive amplifier A, Fig. 1, of alternating, pulsating or oscillating currents, and receiving apparatus d whose indications are 35 observed by the device A, which receiving apparatus in general we will hereinafter mention as the detector or detector circuit. Any suitably sensitive amplification device 40 of the many known may be selected; but we prefer the well-known single or plural-stage audion amplifier or thermionic repeater, of which a species is shown having two audions A' and A² connected to act 45 in succession on the incoming current at terminals a, a', to magnify the oscillation in two stages according to known constants inherent in the apparatus, without any considerable distortion in form of the indication 50 received, thus enabling a very feeble oscillating current at a, a', to be powerfully heard at telephone T.

The instrument A desirably has constants such that at frequencies of about 100 per 55 second the amplification of the impulse at T is not less than about 100 times the intensity of the received oscillation; at frequencies of 400 the amplification is not less than 250 times; at frequencies of 1100 60 amplification is above 300 times; and at frequencies upward of 1500 within the audible limit the amplification is in excess of 400 times the intensity of the incoming impulse. The preferred device comprises at 65 the input end a step-up transformer 2 whose

secondary is connected at one end through lead 4 to the grids 5 of audion A' comprising as usual the said grids 5, mounted between a filament 7, and plates 8, 8, outside of the grids, the whole being enclosed 70 in a vessel exhausted to the desired rarefaction of the contained air or gas.

The other terminal of the coil 4 is connected at 11 respectively to the negative side 75 13 of a filament heating circuit 9 containing a battery b or other source of energy, cathode filaments 7 and 27 and variable resistances 12, 14. The plates 8 of the audion A' are connected by lead 15 to one plate of a condenser 16, and through a 80 lead 18 and impedance coil 17 to one terminal of the primary of an output transformer 20 whose secondary is in series with listening telephone T; and to the positive side of a battery or other source of constant 85 potential b², whose negative side is connected to the filament 7, as at 29.

The other side of the condenser 16 is connected through lead 22 to the grids 25 of the second audion A², and also through 90 lead 11, impedance coil 30 and lead 29 to the secondary of the input transformer 2, to the filament 7 of audion A', and to negative side of battery b². The plates 28, 28, of the audion A² are connected to the 95 primary of the transformer 20 of listening telephone T at 34.

The ionizable gas between the respective filaments 7 and 27 and the respective anode plates 8 and 28 is thus placed under stress 100 by the separate source of energy b², which may be of about 130 volts potential.

It will be understood without detailed explanation that in operation, upon the impact of the oscillation current at terminals a, a', an oscillating flow augmented in amplitude from the source of energy b² is occasioned in the primary of transformer 20 of the listening telephone corresponding in frequency and form of wave to the oscillation at a, a', which induces a flow of current from b² in the space between the hot filaments 7 and the plates 8, said flow being a function of the varying charge on the grids 5; and that in turn the flow of 110 current from b² in the primary 20 is similarly augmented at A² by the augmented charges originating at A'.

When an ordinary microphone transmitter and separate mild source of energy, 120 such as one cell of battery, is connected across the terminals a, a', the disturbance at the telephone T is too violent for any use of the device whatever for the purposes contemplated. The negative side of the battery 125 b², may be connected to earth at E, if desired.

Referring now to Fig. 10, if a plate W of soft iron about 2 feet wide, 2 feet long and about $\frac{1}{8}$ of an inch thick, is connected 130

at the ends of one of its diagonals to the terminals a, a' , by the wires w, w' , there will be found an effect at the amplifier indicative of oscillating differences of potential between w and w' related to the impact upon the plate W of sound waves, (or it may be of electric or magnetic waves associated with the impact of the sound wave) at the plate W . The response of such a plate W to excitation by sound while distinct, is exceedingly faint. There is no source of energy whatever in this form of the apparatus in the circuit $W, w, a, 2, a', w'$, except that created by the phenomenon in question.

15 If now the plate W is surrounded by a few turns w^2 of wire not electrically connected thereto, and this wire is connected across the terminals a, a' , a plainer response to the acoustic excitation of the plate W is at once apparent. This may be due in part to the dynamic motion or bodily vibration in respect to such a coil w^2 of portions of the plate W , and if we can assume either a static charge in the coil or some magnetization of the plate, the behavior of the device may be explained in part as that of a magnetophone or variable capacity transmitter of a type not wholly new; but the assumptions made are not well founded, and 20 all of the phenomena can not be accounted for on these suppositions.

If instead of the plate W (referring to Figs. 11 to 14) a helix w^3 of copper wire is connected across the terminals a, a' , the 25 telephone T will be found to receive very faintly loud, regular sounds in certain ranges of pitch propagated at an angle to the axis of the helix. Sounds propagated along its axis are not received. If a laminated (soft iron wire) core c' , Fig. 13, is entered in the helix, the effect sharply increases in magnitude. If such a helix is wound on a tube f , Fig. 12, of glass or other non-conductor, the behavior of the 40 coil remains the same, the effect being increased by an inductive core c' , and more increased by a tubular soft-iron core c . But if the tube f is made of a conductor, e. g. aluminum, insertion of a magnetically inductive core such as c' is now without effect. 45 If the core is a magnet, the effect is markedly damped or reduced. If a constant source of energy such as one cell or more of a battery is put in circuit with a, a' , the effect ceases.

If during the experiment such a helix and inductive soft-iron core is turned perpendicular to the horizon, in a city, the observer will at once note the increase above 50 his unaided hearing of sounds of traffic, and predominantly of sounds which we have identified as beginning and ending with and changing in pitch with the speeds of and in some way due to the operation of electric 55 motors. Time of propagation of this type

of excitation from a known source at a distance is not at the expected velocity of sound in air but is instantaneous within such mensuration as we have attempted, and is suspected to be at the velocity of light. 70 Each coil selects from its exciting radiations, whether acoustic, electric or magnetic, and reproduces at T , undulations corresponding to sounds of pitches and their overtones peculiar to the particular coil, and 75 probably dependent on the electrical resonance of the closed circuit including it, the character of its core, if any, and the disposition of its spires, as well as upon the periodicity of the waves, or trains of waves, 80 producing the disturbance.

The observer when able to identify a source of the sound most loudly heard, such as a running motor or dynamo of known bearing, will note (see Fig. 26) when the 85 axis of the coil is in a plane (for instance the horizontal plane) nearly including the source a maximum sound when the source is in the (vertical) transverse plane m, m , in respect to the coil; silence when the 90 source is in the polar zones s, s ; and sound nearly at the maximum but lessening toward the polar zones s, s , as the coil is turned through the angles m, s , in respect to the source. The silent polar zones are sharply 95 marked, and depend for angular magnitude on the structure of the coil and its inductive core.

The form illustrated in Fig. 12 and in 100 Figs. 3 and 4 presently to be referred to, is characterized by polar zones of silence decreasing in angular magnitude as the length of the coil is increased relative to its width. If such a coil w^3 with core c' , 105 referring now to Fig. 20, is waterproofed and submerged, and a sheet metal tank Q carrying a running electric motor m resting on a sound-insulating pad q is floated on the water, the coil w^3 is found to transmit the sound of the motor according to the relations 110 of silence and maximum sound distributed about the vertical at the coil w^3 , as shown in Fig. 26 and above referred to. The intensity 115 of the sound received varies with the orientation of the source, but a marked emission is received at the detector at any azimuth of the exciting motor.

Referring now to Figs. 9, 15, 16 and 17, if two like flat coils wound in layers w^7 , w^8 , are connected as shown in Fig. 15, the 120 respective windings being in the direction of the arrows, and the two coils placed in series across the terminals a, a' as indicated, then the impact of either a sound wave or the emission from a motor or alternating current transformer in the direction w' is without effect to produce an oscillation in the circuit $w^7, a, 2, a', w^8$. If now the coil w^8 is replaced by a coil w^9 , Fig. 16, wound in 125 the same direction as the coil w^7 , the con- 130

nections being as before, impact of a wave in the direction x' sets up an oscillation current in the circuit $w^7, a, 2, a', w^8$. If either of the coils w^7, w^8 , is turned into the plane of the direction of the wave x' , as shown in Fig. 17, no oscillation is produced. If such a coil as w^7 is surrounded by a wrapping of iron strips as at i , Fig. 9, sensitiveness is increased.

10 If a number of like coils d^6 , Fig. 17^b, all wound in the same direction and lying in the same plane are connected in series with a, a' , and excited by a constant radiation in the plane of the figure, the intensity of their effect at T will be found to be greater than that of one of them isolated by a wire n' or two of them isolated by a wire n^2 . If now the direction of the oscillation due to two of them be reversed at switch n^3 , there

20 is no response at T .

If a laminated loop of iron wire g^{10} , Fig. 17^a, be wound with a coil w^{15} , and excited by a constant radiation perpendicular to the plane of the loop, giving a sound of a certain intensity at T , the sound is not diminished when the core is cut at y , nor when it is cut away further to y', y^2 , but for a coil w^{15} of a given number of turns, sensitiveness may then be diminished as the core y', y^2 , is

30 shortened beyond a critical length.

Referring now to Fig. 8, if a magnet N S bent into the form of an interrupted annulus of considerable dimensions (and having a natural sound vibration period) be provided with soft iron armatures n^s wound with a few turns of wire w^{10} , and these armatures are placed on the large magnets N S as illustrated in Fig. 8, so as to bridge the gap in the annulus, and the coils on the armatures are then connected as shown in parallel to the terminals a, a' , the resulting instrument will be found to be sensitive to a wide range of sounds approaching it in any direction, the output in the circuit a, w^{10}, a' , being an oscillation wave closely similar to the sound wave but stripped of irregular and noisy overtones. A scratchy phonograph record, for instance, is transmitted by the device of Fig. 8 without the scratchy sounds.

50 The emissions of motors, oscillating discharge circuits, and transformers are also received.

If now, instead of the detector devices mentioned, and referring to Figs. 2, 2^a and 2^b, a laminated ring core of soft iron, for instance, a strip g cut from sheet iron about 1/64 of an inch thick and about 2 inches wide and turned up into a spiral ring g' about 6 inches across is covered with a padding g^2 of cotton batting or felt, and then wound with a vortex winding of about 450 turns of insulated copper wire, for instance about No. 18, an instrument d' as shown in Fig. 1 having marked sensitiveness is formed.

65 If now the detector d' is connected in series with terminals a, a' , and placed to receive the impact of a sound wave propagated in the direction of the arrow x , Fig. 19, as shown at I, with the central axis of the ring in direction x , the sound is transmitted to the telephone T with extraordinary vigor and clearness. That is to say, this occurs if the sound does not in the particular instance mentioned fall below a pitch of about 200 vibrations per second or exceed a pitch of

70 about 10000 vibrations per second. Within these limits musical sounds and articulate speech arriving in the direction of the arrow x , that is to say, in the axis of the torus, are transmitted with great purity of reproduction, and the better transmitted the better the resonance and purity of the sounds received. Certain classes of noises such as pouring water into a vessel, scratching sounds, and dull rubbing or rumbling sounds, are transmitted either not at all or very faintly.

If the position of the detector d' is as at II or III the response at the telephone T is feeble.

Referring to Fig. 18, a small oscillating circuit and spark gap h as indicated in the diagram, at distances up to several hundred feet, with a spark of half a millimeter, is audible at the telephone T when the instrument d is in the position I with respect thereto. Turning the instrument d' to the positions II or III does not very greatly change the effect.

Referring to Fig. 19, the blast of a small organ pipe p (512 vibrations per second) at about 400 yards and inaudible to the observer is transmitted clearly when within five or ten degrees of the direction x , the instrument d' being in position I. When the instrument is turned to the position II or III the organ pipe at this distance is inaudible. Time of transmission of the sound is the expected time of the sound-wave in air.

We do not fully know and therefore do not undertake to explain with authority the reasons for the behavior of the apparatus mentioned. Upon the classic researches of Clerk Maxwell, Hertz and Rutherford, we may state, for hypothesis only, (1) that an oscillatory discharge between capacities radiates into space waves whose fronts are in one dimension a disturbance of the ether in an electric sense, and in another dimension in a magnetic sense [Maxwell] (2) that as employed in space telegraphy such radiations are plane-polarized in planes vertical to the horizon and that this dimension is that of manifestation of the electric energy of the wave [Hertz], (3) that rapid electric oscillations of the period of such waves when taking place in a coil surrounding a magnet not only have a demagnetizing effect but also suppress the hysteresis in iron bodies in a changing or

fluxing state of magnetism. [Rutherford; Marconi; C. Maurain; E. Madelung].

From this, it follows that such a wave whether or not plane-polarized in the direction of its magnetic effect may directly (a) shift the molecular structure or magnetic constancy of a mass of iron (b) directly affect a conductor circuit having parts in and parts not in the plane of polarization, and 10 therefore cause a difference of potential between the parts of said circuit; or (c) in the case of a closed circuit having a magnetically inductive relation to a body of iron exposed to such waves, cause a difference of 15 potential and flow in said circuit due both to cause (a) and to cause (b).

For further hypothesis, we conceive that a body having a rapidly changing magnetism, such as the field of a motor or dynamo 20 or core of a transformer (d) emits Maxwell's or Hertz's waves by stress on the ether much as the charge in a condenser sets up a stress in the dielectric surrounding it, but (e) that these waves are plane-polarized in 25 the direction of their magnetic manifestation, and hence are imperceivable by the electric wave detectors of common knowledge; (f) that their energy is nevertheless available at a distance to induce an electromotive 30 force in conductors arranged according to the present disclosure.

From the experiments noted above, we further conclude that a hysteretic or intra-molecular change in a metal under impact 35 of such waves is an observed fact.

We further advance for hypothesis only that a change having a similar effect on the metal conductors and cores mentioned is induced by acoustic vibrations of certain frequencies, if not of all frequencies, and that 40 such electromagnetically produced and acoustically produced change in the cores or coils, or both, of the described apparatus is the causative factor in the observed potential differences changing at the frequency of 45 the original impulse, as found in detector circuits of the general type herein mentioned when exposed to excitation by radiations having a magnetic or acoustic component.

For practical utilization, referring to Fig. 21, such an instrument as d' may have its wire coil covered with paraffin or other waterproof insulating protective coating, and be used submerged to detect submarine 55 radiations. A submarine bell B of the existing type on our coasts, for an instance of such uses, has been observed to excite such a detector d' at distances of 2½ miles, with no indication that the maximum distance was 60 approaching. Neither passing steamships, the wash of the water, nor the internal noises of the vessel V from which the detector d' was suspended overboard and on which instrument A was carried, were confusingly 65 audible. The noises of the screws, of the

water washing on the instrument and the vessel were inaudible, and the sounds made by the reciprocating engines of the vessel V and passing water-traffic were audible only as a faint background for the bell signals. 70 When the detector was submerged in an internal water-tank at the bow of the vessel V, the signal sounds were little diminished or confused, but indication of their direction made by turning the detector was no longer 75 reliable.

It will be understood that the detector d' is but one instance of detectors having capacity to respond to acoustic or other radiant wave excitation and to indicate the direction 80 of the wave. For instance, as shown in Fig. 6, the core g⁴ of an annulus such as d' may be made of a coil of many turns of soft iron wire with advantage; or as detector d² may be wound endwise through and on an elongated solid or laminated tubular core g⁵, Fig. 6^a; or radially on a disk core g⁶, Fig. 7; or a tubular soft iron core g², Fig. 3, may be wound with several layers of relatively coarse insulated wire w⁴ as shown in Fig. 3, to form a detector d³. Another form of detector d⁴, Fig. 4, may comprise a wood or fibre spool g⁷, a core formed of a bundle g⁸ of soft iron wires, and a winding w⁵ of relatively coarse wire. Or as shown in Figs. 5⁹ and 5^a, an annular iron channel g⁹ with a peripheral coil w⁶ may comprise another form of detector d⁶. The detector d⁶ has a narrow angular range of maximum sensitivity to radiations propagated in or near the relative direction x², and a wide zone of silence when the axis of the detector is placed in or on either side of the direction of propagation of the wave, as shown in Fig. 26^a.

In respect to the three general types of detector which are merely illustratively shown at d³, and d⁴ for one type, at d' for another type, and at d⁶ for a third type, the first type (d³, d⁴) is characterized by sharply marked polar zones of silence, so that absence of indication of a radiation as the detector is turned with respect to the source of the radiation is indicative that the direction of propagation of the radiation lies 110 within a few degrees of the direction of the axis, the direction being capable of being found within a degree or two of arc by taking the mean between recurrences of the sound on oscillation of the detector in one direction and in the other direction. The second type (represented by d') is more delicately sensitive to a wider range of acoustic sounds than the type d³, d⁴, but gives a less positive indication of the direction of propagation of acoustic, magnetic or electric waves. The third type (d⁶) is characterized by a wider zone of silence than the other types, and a more definitely marked maximum when the plane perpendic- 115 120 125 130

ular to its axis is in the line of propagation of the radiation. In the types d^3 and d^6 sensitiveness to emissions such as made by operating electric motors as compared with 5 acoustic sounds is more marked than in type d' .

Referring now to Figs. 22, 23, 24 and 25, it is obvious that the peculiarities of either 10 type of detector may be taken advantage of by suitable auxiliary devices. If a cylindrical shield S of magnetic material, such as soft sheet iron, is provided in a vertical position, and a detector d^3 placed axially therein, it will be observed that indications 15 from the detector cease. Now turn the shield S in a horizontal position, Fig. 23, and the detector d^3 remains insensitive to radiations propagated in any horizontal or vertical direction. But if the detector d^3 20 is turned into the position shown in Figs. 24 and 25, the detector will be found to be insensitive to radiations proposed in the direction x^3 , x^3 , but sensitive to those propagated in directions along or nearly in the 25 direction of the axis of the shield S (perpendicular to the plane of the figures).

Each form of detector described has been found selectively to transmit, in respect to 30 sound waves, and periodically recurring magnetic or electric waves pure tones and their harmonics in preference to mixed and broken tones. By hypothesis and experiment, the pitch sensitiveness of each detector has as factors the number of spires or turns 35 of wire upon it, the quality, weight, distribution and dimensions of the magnetically inductive mass comprised in it, the capacity of the detector, and the capacity, inductance and impedance of the transformer 40 of and leads to the amplifier A. In the case of detectors of the type d^3 , d^4 , the longer the core and the more the turns of wire, the lower in pitch are the waves or recurring wave-trains strongly exciting the detector 45 circuit. In the case of the type d^6 , the narrower and larger the annulus, the more marked is the sensitiveness to direction of propagation in the plane of the annulus.

Detectors of the types d^3 , d^4 , or d^6 , and other types to lesser degrees, are serviceable 50 as indicators of the direction of propagation of plane polarized electric or Hertz waves impinging upon them. When the polar axis of such a detector is perpendicular to the direction of a known source of such waves, the telephone T is responsive. Turning the detector through a few degrees of arc away 55 from this position (how far depending on the vigor of the signal) extinguishes the indication from such waves. Quantitatively, such detectors give but feeble responses to the usual signals as compared with many known forms of wireless receiving apparatus, but we are not aware of any prior

apparatus indicating the direction of the 65 wave with such certainty.

We may utilize the selective sensitiveness of detectors of the genus described in many different ways. As mentioned above, each type appears to be sensitive in a superior 70 degree to high-pitched emissions found to be made by running, starting and stopping electric motors, by alternating current transformers, and by dynamos. The invention therefore affords a method of and means for 75 detecting the approach and position of a vessel containing operating electric motors, transformers or dynamos by selectively perceiving and determining the direction of propagation of the radiations emitted in or 80 above the water by such a vessel.

Referring to Figs. 27, 28, 29 and 30, an observing vessel V' may be provided with a mounting D for detector d of one of the types indicated above, and means for turning this detector in azimuth and in altitude to known departures from the fore and aft axis of the ship. One instance as shown in Fig. 27, of convenient means, may comprise a manhole 50, and stuffing-box gland 51 in 90 the ship's bottom in which gland is journaled a tubular shaft 53 having an index sector 54 and handle 55 fast thereto above an upper bearing 56, which may be on deck, and may carry a graduated azimuth circle 95 57. At its lower end the shaft 53 carries a fork 60 in which horizontal trunnions 61 on a saddle 62 are journaled. Saddle 62 carries a detector d whose polar axis is at right angles to the trunnions. Saddle 62 and detector d are preferably arranged to be turned on the axis 61 to known altitudes 100 of the polar direction of the detector d. For instance, a bevel gear sector 63 attached to saddle 62 is adapted to be turned by a meshing bevel gear 64 on a tubular altitude shaft 65 within shaft 53, and having an index 66 and handle 67 for reading in respect to the index sector 54 departure of the polar axis 105 of the detector d from the horizontal. Current leads 70 from detector d to terminals a, a, of amplifier A are carried within shaft 65.

Referring to Fig. 30, suppose the altitude shaft 65 at D be turned so that the polar axis of the detector, such as d^3 , is vertical. Then, bearing in mind the nearly maximum sensitiveness on a wide arc central on the transverse axis of the detector, approach 115 of a submarine U having a running motor or dynamo abroad at any bearing to the ship V' gives warning by a loud, high-pitched hum audible at telephone T. The observer immediately turns the altitude handle 67 to position the detector with its axis horizontal. 120

If the azimuth handle 55 is positioned on the fore and aft axis, and the submarine U 125

is abeam either to port or starboard, the sound continues. But if the submarine is dead ahead or astern, the silent polar zone of detector d covers it, and the sound ceases at T. Whenever the indication is abeam, the observer sweeps the handle 55 to find the bearing of the maximum plane, and then the center of the silent zone. The latter reading gives the bearing of the source of the sound within a few degrees of arc. The whole operation has taken but a few seconds.

Whether the sound is ahead or astern (or to port or starboard) of the plane found is still unknown. To determine this the ship may carry fixed or movable detectors D^3 , D^4 , on her sides. These may be of any type, such as the type d' . By suitably arranged leads and a commutator switch 80, Fig. 31, at the observer's station for connecting these to amplifier A, the indication at D^3 , D^4 , may be listened for in succession. The damping effect of the ship V' will now render the indication from D^3 or D^4 stronger as the submarine is to port or starboard.

By the means indicated the ship's course may be directed toward the source of the sound, and corrected if it deviates.

In Figs. 28 and 29 a mounting for detectors of the "wreath" type d^6 is shown. The ship V³ is provided with bearing brackets 71, 71, for an overboard vertical shaft 72, which may be tubular to house the current leads 73, and terminate in a fork 74 in which a horizontal detector d^{61} is pivoted for a limited motion on trunnions 75 as controlled by a link 76 and bell-crank lever 77 having a pointer 78 reading on a sector 78 on a sprocket wheel 79 fast to the top of shaft 72. A chain 81 to inboard hand-wheel 82 on a standard 83 provides a convenient azimuth adjustment for shaft 72, which may be read at a compass 84. A vertically placed detector d^{61} is fastened to shaft 72 at right angles to trunnions 75. A double-pole switch 85 serves to connect either d^{60} or d^{61} to the amplifier A at will.

Detector d^{60} is sensitive in all horizontal directions. Having given warning of a submarine U, contact at 85 is switched to detector d^{61} , and the wheel 82 turned to sweep the vertical sensitive plane of detector d^{61} past the direction of the source, which is read at the compass 84 when found. Detector d^{60} may be moved by lever 77, when the submarine is near by, to give direction by inclination to the horizontal of its plane of maximum sensitiveness, and indication of its depth, the switch 85 being again shifted when the bearing in azimuth is known.

It will be apparent that two boats V', V², equipped with the devices mentioned may point to and either converge upon the submarine U, one of them attacking her when

dead ahead of the other (and so over the source of the radiation) or by the intercept of their fore and aft lines giving an infallible indication of the position of the submarine for a third vessel equipped to capture or destroy. Or a merchantman equipped with the device may be given indication of a safe direction of retreat and constant warning of approaching danger.

Vessels equipped with our device may exchange signals either by a submerged bell, a submerged magnet excited by an alternating current adapted to be made and broken, by causing spark discharges or other sources of excitation at a distance, or by other wave-emitting means not forming a part of the present invention, giving a wave recurring within the pitch-sensitivity of the particular detectors adopted.

In some cases a single vessel may be provided with two or more detector stations at known distances apart in order to determine bearing and distances of a submarine or other source of radiations by the azimuth of the respective detectors with respect to the line joining them. For this and other purposes, such a detector may be mounted on a float towed behind a vessel, not shown. A single vessel equipped with the described devices may rely upon a detector mounted to be moved on a horizontal axis, or fixed with its sensitive plane in the vertical, to indicate when the submarine is immediately below her, having approached on the line of propagation of the emission from the motors. In either case, finding the enemy and his destruction is made certain.

We have hereinafter referred to the phenomena of the creation of a relatively feeble oscillating flow in the detector circuits described by an acoustic disturbance, as a "direct" conversion of the acoustic wave energy into electrical disturbance. This is to be distinguished from first mechanically transforming the sound wave energy into motion of a diaphragm, a magnetic body, or a member of an inductive couple, and then converting mechanical energy of this moving mass into an electrical disturbance. The direct conversion referred to avoids the transformation of the radiant energy into mechanical motion.

We claim:

1. The art of perceiving radiant energy of acoustic type comprising transforming the energy of an undulation of such type into a corresponding and perceptible electric current in a conductor coil having therein a uniform potential except when excited by exterior acoustic energy arriving in a certain direction in relation to said coil and causing the said current to produce an amplified current in an observation instrument.
2. The art of perceiving the direction of

propagation of sounds comprising contemporaneously transforming the energy of the acoustic wave into electrical energy in a detector circuit capable of being excited to 5 different degrees of electric energy according to the direction of propagation of the sound at the detector, and containing no other source of energy, and observing the 10 amplitude of the electric energy during different orientations of the detector.

3. The art of perceiving wave-disturbances in media capable of acoustic vibration comprising direct conversion of a part of the energy of the acoustic wave-disturbance 15 into a relatively feeble electrical disturbance in a conductor immersed in said medium and causing amplification of the said electrical disturbance.

4. The art of perceiving wave-disturbances in and of media capable of acoustic vibration comprising direct conversion of the energy of the wave-disturbance of the 20 medium of transmission into electrical dis-

turbance of like frequency in a conductor immersed in said medium.

5. The art of perceiving wave-disturbances in and of media capable of acoustic vibration comprising direct conversion of the energy of the wave-disturbance of the medium of transmission into electrical disturbance of like frequency in a conductor immersed in said medium and employing the electrical disturbance so created to excite the flow at like frequencies of local currents of much greater magnitude adapted to be 30 35 audible in a telephone receiver.

6. The combination of a direction-sensitive sound-wave detector, and amplifier for receiving indication therefrom, and a mounting for the detector permitting it to be 40 turned in altitude and azimuth.

Signed by us at Boston, Massachusetts,
this eleventh day of April, 1918.
